UNITED STATES PATENT OFFICE.

THOMAS MASON HUGHES, OF SAN JOSE, CALIFORNIA.

RAILWAY-CROSSING.

1,073,760.

Specification of Letters Patent. Patented Sept. 23, 1913.

Application filed May 21, 1913. Serial No. 769,083.

To all whom it may concern:

Be it known that I, THOMAS MASON HUGHES, a citizen of the United States, residing at San Jose, in the county of Santa Clara and State of California, have invented a new and useful Railway-Crossing, of which the following is a specification.

The present invention appertains to railway crossings, and aims primarily to provide a noiseless crossing.

It is the object of the present invention to provide a noiseless railway crossing of the most simple, durable and inexpensive construction possible, and which shall be efficient in its use.

With the foregoing general object outlined and with other objects in view, which will be apparent as the description proceeds, the present invention resides in the combination and arrangement of parts and in the details of construction hereinafter described and claimed it being understood that changes in the precise embodiment of the invention can be made within the scope of what is claimed, without departing from the spirit of the invention.

The invention has been illustrated in its preferred embodiment in the accompanying drawing, wherein:—

Figure 1 is a plan view of the improved crossing, portions being broken away. Fig. 2 is a sectional view of the crossing, taken on the line 2—2 of Fig. 1. Fig. 3 is an enlarged cross section of one of the rails of the crossing showing flanged wheel in raised position.

Referring specifically to the drawing, the numerals 1 designate the rails of one track, while the numerals 2 designate the rails of the other track crossing the aforesaid track. Each of the rails is provided with a relatively thick web and is further provided with an upstanding guide flange 3 spaced inwardly from the tread and providing a flange groove 4 adapted to receive the flanges of the car wheels. The grooves 4 beyond the crossing points have a depth equal to the width of the flanges of the car wheels, the grooves, however, being somewhat wider than the flanges of the car wheels. In practice, the ordinary depth of the grooves 4 will be about one inch, that is, beyond the points of intersection of the rails.

In carrying out the present invention, the grooves 4 are made shallower between the rails of the respective tracks, the shallow

portions 4' extending beyond the rails of the respective tracks for a distance in practice, of approximately one foot to the points 5. From the points 5 to the points 6, the grooves 4 are inclined, the distance between the respective points 5 and 6 being, in practice, approximately three feet, so that the rise is gradual, the rise being approximately three-eighths of an inch in practice.

The rails are complete in themselves, the present invention eliminating all encumbering parts. The rails 1 of the respective or main track, extending unbrokenly from one side to the other of the crossing, while the rails 2 are formed in sections, the ends of the sections being coped or matched to the sides of the rails 1, and the treads and guard flanges 3 of the rails 1 being provided with the transverse grooves 4' registering with the grooves of the rails 2. The ends of the sections of the rails 2 are fastened securely or rigidly to the rails 1, angle plate 7 being bolted, riveted or otherwise secured to the webs of the respective rails. The respective rails are mounted on any suitable base, the usual ties being preferable, with the base flanges of the rails spiked to the ties.

The car wheels in approaching the crossing will cause the flanges of the car wheels to gradually ride upon the respective inclined portions of the grooves 4 between the points 5 and 6, and the wheel flanges in gently riding upward on the inclined portions, will raise the treads of the wheels above the balls or treads of the rails, the wheels passing over the crossing in raised condition. As the wheels leave the crossing, the flanges will ride gently down the respective inclined portions of the grooves to again bring the wheel treads gradually upon the treads of the rails. As a result of the relatively long inclined portions of the grooves, and the raised portions between the rails of the respective tracks extending beyond the respective rails, the wheels may pass readily and noiselessly over the crossing, and without danger of jumping the track or causing any other damage. The wheels may also pass rapidly over the crossing, so that a slackening of the speed is not necessary, it being possible in practice, for the train to pass over the crossing while going at a considerable rate of speed or velocity.

Attention is directed to the fact that the crossing merely embodies the four rails, and

the angle plates for attaching the rails together, so that no additional parts are necessary, which would be liable to encumber or burden the crossing. It will thus be manifest that the objects aimed at have been carried out satisfactorily, and that the present crossing is a most efficient and desirable one.

What is claimed as new is:—

- 10 1. In a railway crossing embodying two pairs of rails crossing each other, each rail having a relatively thick web and an upstanding guard flange spaced inwardly from its tread to provide a groove, the grooves being relatively deep considerably beyond the respective rails and being relatively shallow between and slightly beyond the respective rails, the grooves having relatively long gradual inclined portions between the shallow and deep portions.
- 15 2. In a railway crossing, two pairs of

rails crossing each other, one pair of rails extending uninterruptedly from one side of the crossing to the other, and the other rails being formed in sections having their ends coped to the sides of the aforesaid rails, and angle plates secured to the webs of the respective rails, each of the rails embodying a flange groove, the grooves being relatively shallow between and slightly beyond the respective rails and then having relatively long and gradual inclined portions, the rails of the first mentioned pair having lateral grooves registering with the grooves of the other rails.

In testimony that I claim the foregoing as my own, I have hereto affixed my signature in the presence of two witnesses.

THOMAS MASON HUGHS.
